UNITED STATES PATENT OFFICE.

JAMES BLAINE REPLOGLE, OF CHICAGO, ILLINOIS, ASSIGNOR TO JOSEPH SALTZMAN, OF CHICAGO, ILLINOIS.

ELECTRIC CLOTH-CUTTER.

No. 828,681.

Specification of Letters Patent.

Patented Aug. 14, 1906.

Application filed April 29, 1905. Serial No. 258,074.

To all whom it may concern:

Be it known that I, JAMES BLAINE REPLOGLE, a citizen of the United States, and a resident of Chicago, in the county of Cook and State of Illinois, have invented a new and Improved Electric Cloth-Cutter, of which the following is a full, clear, and exact description.

My invention relates to cloth-cutting machines, my more particular object being to produce a power-driven cutter operated, preferably, by electricity and combining certain advantages hereinafter described.

Figure 1 is a side elevation showing my cutter ready for use, certain parts being broken away for the sake of clearness. Fig. 2 is a front elevation of the same. Fig. 3 is a plan view of the cutter ready for use. Fig. 4 is an enlarged elevation of the upper end of the connecting-rod 17, the pin 19 being shown in section. Fig. 5 is an enlarged sectional view through the upper end of the connecting-rod 17. Fig. 6 is a section upon the line 6 6 of Fig. 1 looking in the direction of the arrow and showing one of the baffle-plates, together with the knife and its mountings. Fig. 7 is a side elevation of the knife removed from the cutter. Fig. 8 is a section upon the line 8 8 of Fig. 1, showing the bowl for supporting the motor and the rib for supporting the bowl; and Fig. 9 is a fragmentary section somewhat similar to Fig. 8, but showing the section as taken upon the line 9 9 of Fig. 1 looking in the direction of the arrow.

An electric motor 10 is provided with a shaft 11, revolvably mounted in bearings 12, and is provided with other bearings 13 14, which carry a revoluble shaft 15. Mounted upon the shaft 15 is a fly-wheel 16, which supports a connecting-rod 17, the upper end 18 of the connecting-rod being journaled upon a crank-pin 19. The crank-pin 19 is provided with an oil-groove 20 (see Fig. 4) and is encircled by a bearing-sleeve 22, threaded into the head 18 and provided with spanner-holes 21, whereby it may be turned, and thus removed or adjusted to make a proper fit upon the crank-pin 19, so as to compensate for wear. The bearing-sleeve 22 is made of spring metal and is split at 23, being thus free to expand. The lower end of the connecting-rod 17 is provided with a head 24, which engages a pin 25 carried by an adjust-

able bracket 26, and secured rigidly to the bracket 26 by means of a thumb-screw 28 is a stem 27 of a knife 30, this knife being provided with a serrated edge 31 and being hollow-ground, its general shape approximating that of a razor-blade, as indicated in Fig. 7. A guiding-sleeve 27^a is mounted upon an annular bracket 29 and supported thereby so as to guide the stem 27, which is free to slide vertically. A rib 32 is rigidly connected with a handle 33, so that the latter may be used for manipulating the device as a whole. Extending downwardly from the rib 32 and mounted upon opposite sides of the knife 30 are guides 34. Immediately back of these guides and partially encircling the back of the knife is another guide 35. The guides 34 are connected together by means of baffle-plates 36 and terminate at the bottom in a smooth plate 38, the guide 35 also terminating in a comparatively large plate 37, these plates fitting together neatly, as indicated at the bottom of Figs. 1 and 2. A guide-sleeve 39 is integral with the annular bracket and is mounted rigidly upon the rib 32. Screws 40 connect the rib 32 with the guides 34, as indicated in Fig. 2. A brace 40 serves to increase the rigidity of the sleeve 39 relatively to the rib 32. The motor 10 rests in a bowl 42, which in turn rests upon the rib 32, the latter being supported by the guide-stem 35.

My invention is used as follows: Power being applied to the electric motor 10, the revoluble shaft 15 is caused to turn. The fly-wheel 16 thereupon rotates and acting through the connecting-rod 17 confers a reciprocating vertical movement upon the stem 27 of the knife. The serrated edge 31 thus reciprocates vertically. The handle 33 is now grasped by the operator, and the front part of the plate 37 is passed under the cloth to be cut, the edge of this cloth passing easily between the lower baffle-plate 36 and the upper surface of the plate 38. The entire device may be moved somewhat after the manner of a pair of shears, so as to cut the cloth in any desired shape. Similarly the device may be held still and the cloth fed against the cutting edge of the knife. The cloth is prevented from following the movement of the knife because of the fact that the cloth is unable to pass the baffle-plates 36 and is held against these baffle-plates while the serrated edge of the knife makes its successive strokes.

As indicated in Fig. 6, the guides, considered together, have a wedge-like conformity, and thus serve as a spreader for the cloth after the same passes the cutting edge of the 5 knife and is divided. The feed of the cloth is therefore rendered comparatively easy.

When the device is used for cutting comparatively thin layers of cloth—as, for instance, single pieces used for an individual 10 garment—only the lower baffle-plate 36 is called into use. When, however, a large number of layers of cloth are to be cut simultaneously, the machine is fed directly against the edge of the “stack,” the several baffle- 15 plates 36 finding their way between the layers of cloth, each consecutive pair of baffle-plates serving to prevent undue movement of such layers of cloth lying therebetween. The cloth is thus effectively prevented from being dragged out of position by 20 movement of the knife, and consequently large quantities of the cloth can be cut according to the same pattern.

It should be noted that the fly-wheel 16 25 absorbs energy at any moment when the knife happens not to be actually cutting the cloth, and the power thus stored is utilized when the edge of the knife makes contact with the surface to be cut. The guides 34 30 35 together form a sort of hollow bar having a triple function—that is, it serves as a sheath for the knife, a support for the baffle-plates, and a spreader for the cloth.

Having thus described my invention, I 35 claim as new and desire to secure by Letters Patent

1. The combination of a knife provided with a serrated edge, means for causing said knife to reciprocate, a plurality of stationary 40 baffle-plates disposed adjacent to said knife and partially encircling the same, motor mechanism for actuating said knife, and a plate disposed adjacent to said knife and provided with a surface for entering between the 45 layers of the cloth.

2. The combination of a knife, means for actuating the same, a composite stem built partially around said knife and serving as a guide therefor, baffle-plates mounted upon 50 said stem and disposed adjacent to said knife, and a handle for manipulating the general position of said knife and said baffle-plates.

3. The combination of an electric motor, a 55 bowl for supporting the same, a handle connected with said bowl, a rod likewise connected with said bowl, a plate disposed at the extremity of said rod and adapted to enter between layers of cloth, guides connected 60 with said rod, a knife intermediate of said guides, and mechanism connecting said knife with said motor so as to enable said knife to be driven thereby.

4. The combination of a rib, a handle connected therewith, guide members connected 65 with said rib and extending longitudinally therefrom, a rod disposed adjacent to said guide members, a knife disposed intermediate of said guide members and provided with a back portion engaging said rod, a plate connected with said guide members and with said rod, said plate being provided with a portion for entering between layers of cloth, baffle-plates mounted upon said guide members and partially encircling said knife, and 70 connections from said knife to said motor whereby said knife may be driven.

5. The combination of a hollow-ground knife provided with a blade portion and with a stem, mechanism connected with said stem 80 for reciprocating said knife, guide members engaging said blade portion, another guide member engaging said stem, and plates connected with said guide members for the purpose of entering between consecutive layers 85 of the material to be cut.

6. The combination of a portable frame, a motor carried thereby and provided with a fly-wheel, a connecting-rod engaging said fly-wheel and driven thereby, a knife secured to 90 said connecting-rod and reciprocated by movements thereof, guides for said knife, baffle-plates disposed adjacent to said knife for preventing undue movement of the material to be cut, and mechanism disposed adjacent to said knife and provided with a surface to be inserted intermediate of the layers 95 of the material to be cut.

7. In a cloth-cutter, the combination of a frame, a movable knife mounted therein, said 100 knife being provided with a hollow-ground edge, baffles mounted upon said frame at a point adjacent to said knife, motor mechanism, and connections from said motor mechanism to said knife for the purpose of actuating the same.

8. The combination of a frame, a knife mounted therein and provided with a serrated edge, baffles mounted upon said frame adjacent to said serrated edge, and means for 110 actuating said knife relatively to said baffles.

9. The combination of a frame, a bracket mounted thereupon, baffles connected rigidly with said bracket, a reciprocating knife mounted within said bracket, motor mechanism provided with a fly-wheel, and connections from said fly-wheel to said knife for the purpose of actuating the same.

In testimony whereof I have signed my 120 name to this specification in the presence of two subscribing witnesses.

JAMES BLAINE REPLOGLE.
